UNITED STATES PATENT OFFICE.

OREN E. HOLTSCLAW, OF ELWOOD, INDIANA, ASSIGNOR OF ONE-HALF TO G. I. SELLERS & SONS COMPANY, OF ELWOOD, INDIANA, A CORPORATION.

HOLDER FOR ELECTRIC FUSES.

Application filed April 21, 1925. Serial No. 24,834.

This invention relates to holders for electric fuses, and has for one of its objects the provision of a device of this character which shall be adapted to hold a fuse perfectly ⁵ tight without the aid of springs.

A further object of the invention is the provision of a fuse holder which shall be adapted to permit the application or removal of a fuse without the formation of an ¹⁰ arc.

A further object of the invention is the provision of a fuse holder which shall be adapted to permit the ready application or removal of a fuse, to establish a good electrical ¹⁵ contact between the leads and the fuse, and to prevent the accidental displacement of the fuse.

A still further object of the invention is the provision of a fuse holder which shall be ²⁰ simple, durable and inexpensive of manufacture.

The foregoing and other objects are attained by the construction, combination and arrangement of parts hereinafter fully described and claimed, and illustrated in the accompanying drawing, wherein:

Figure 1 is an elevational view of a fuse holder constructed in accordance with my invention,

Figure 2 is a view in end elevation of the fuse holder,

Figure 3 is a transverse sectional view of the fuse holder, the section being taken on the plane indicated by the line 3—3 of Figure 1,

Figure 4 is a longitudinal sectional view of the fuse holder, the section being taken on the plane indicated by the line 4—4 of Figure 1, and

Figure 5 is a detail sectional view taken on the plane indicated by the line 5—5 of Figure 3.

Corresponding and like parts are referred to in the following description, and designated in the several views of the accompanying drawing, by similar reference characters.

The fuse holder comprises a base 1 which may be made of slate, porcelain, marble or other suitable material. Metal strips 2 provided with outstanding ears 3 are secured to the base 1 in relatively spaced relation and are connected to binding posts 4 by conduct-

tors 5. Clamps each of which consists of a relatively fixed jaw 6 and a relatively movable or pivoted jaw 7, are provided for the reception of the ends of a fuse 8 which is of the cartridge type and shown merely for the purpose of illustrating the manner in which the holder is adapted to support a fuse. The fixed jaws 6 are secured to the strips 2 by bolts 9 which also function as retainers for the inner ends of the conductors 5. The movable jaws 7 are pivotally connected to the ears 3 by bolts 10. These parts are provided with opposed arcuate recesses 6^a and 7^a ⁵⁵ for the reception of the ends of the fuse 8. The jaws 6 are provided with fingers 6^b to prevent any casual endwise movement of the fuse 8 while the latter is being secured to the holder. The jaws 7 are adapted to be secured in active or fuse retaining position by cams 11 pivoted to the ears 3 by bolts 12. The cams 11 are made of fibre or any other suitable insulating material, and are connected together so that they may be simultaneously moved into active or inactive position by a hand bar 13 which is also made of fiber or other insulating material. The ends of the hand bar 13 are reduced as indicated at 14, and said reduced ends are let in and secured to the cams 11. Insulating spacing sleeves 15 are mounted upon the bolts 12 between the ears 3 and the cams 11 and maintain the latter in position for contact with the central portions of the outer sides of the ⁶⁰ movable jaws 7.

When it is desired to either apply a fuse to or remove it from the holder, the cams 11 are swung out of contact with the movable jaws 7 and the latter swung away from the fixed jaws 6. The fuse 8 may now be readily positioned upon the fixed jaws 6 or removed therefrom without danger of forming an arc. To secure the fuse in place, it is only necessary to swing the cams 11 in the direction of the fixed jaws 6. This carries the movable jaws 7 into contact with the ends of the fuse, and they may be held in contact therewith under the pressure necessary to establish a good electrical contact between the conductors 5 and the metal ends of the fuse 8. ⁷⁰ ⁷⁵ ⁸⁰ ⁸⁵ ⁹⁰ ⁹⁵ ¹⁰⁰

It should be understood that the drawings are merely illustrative and do not pretend to give exact proportions. Furthermore, the

said drawings are illustrative of a preferred construction, it being my expectation that various changes and modifications may be made without departing from the spirit and scope of the invention.

What is claimed is:—

1. A fuse holder comprising a base, fixed jaws secured to the base, movable jaws connected to the base, and simultaneously operable cams connected to the base and cooperating with the movable jaws to retain them in fuse clamping position.
2. A fuse holder comprising a base, fixed jaws connected to the base, movable jaws connected to the base, movable jaw actuating and retaining cams connected to the base, and a hand bar connected to the cams to simultaneously operate them.
3. A fuse holder comprising an insulating base, strips secured to the base and provided with ears, resilient relatively fixed jaws secured to the strips, movable jaws pivoted to the ears, simultaneously operable cams connected to the ears for holding the movable jaws in fuse clamping position, binding

posts, and conductors connected to the binding posts and fixed jaws.

4. A fuse holder comprising a base of insulating material, metal strips secured to the base and provided with ears, jaws secured to the strips, other jaws pivotally connected to the ears, binding posts, conductors connected to the jaws and binding posts, cams of insulating material connected to the ears for cooperation with the pivoted jaws to hold the latter in fuse clamping position, and a cam operating bar of insulating material bridging the cams to simultaneously operate them.

5. A fuse holder comprising a base, fixed jaws connected to the base, movable jaws connected to the base, cams of insulating material connected to the base and cooperating with the movable jaws to hold them in fuse clamping position, and a cam operating bar of insulating material bridging the cams to simultaneously operate them.

In testimony whereof I affix my signature.

OREN E. HOLTSC LAW.
